UNITED STATES PATENT OFFICE.

JOHN VAN VLECK, OF NEW YORK, N. Y.

DESIGN FOR A CASE FOR ELECTRICAL MEASURING-INSTRUMENTS.

SPECIFICATION forming part of Design No. 23,299, dated May 22, 1894.

Application filed April 13, 1894. Serial No. 507,477. Term of patent 14 years.

To all whom it may concern:

Be it known that I, JOHN VAN VLECK, of the city, county, and State of New York, have invented and produced a new and original 5 Design for Cases for Electrical Measuring-Instruments, of which the following is a specification.

The accompanying drawing represents an instrument case in perspective showing my 10 design.

The leading and characteristic feature of my design is the configuration of the instrument case, which has two sides, one convex in the form of a circular arc and the other 15 straight. The opposite sides of the case, one

of which is shown at A, are flat and parallel. The edge or periphery of the case is of much less width than the side A. The said periphery B is in the form of an arc of a circle, of which the straight side C of the case forms 20 the chord. Around the edges of the straight side C appears a flange, D.

I claim—

The design for an electrical measuring instrument case substantially as herein shown 25 and described.

JOHN VAN VLECK.
